(57) **CLAIM**

The ornamental design for a baseball training mat, as shown and described.

DESCRIPTION

FIG. 1 is a perspective view of a baseball training mat. FIG. 2 is a front view of the baseball training mat. FIG. 3 is a back view of the baseball training mat. FIG. 4 is a right side view of the baseball training mat. FIG. 5 is a left side view of the baseball training mat. FIG. 6 is a top view of the baseball training mat; and, FIG. 7 is a bottom view of the baseball training mat. The baseball training mat can be used, for example, for training beginners in baseball or softball batting.

1 Claim, 5 Drawing Sheets
